CLAIM

I claim the ornamental design for a column protector, as shown and described.

DESCRIPTION

FIG. 1 is a front perspective view of a column protector panel, showing my new design;

FIG. 2 is a rear perspective view thereof;

FIG. 3 is a front elevation view thereof;

FIG. 4 is a side elevation view thereof; and

FIG. 5 is a top plan view, the bottom being identical thereto thereof; and,

FIG. 6 is a rear elevation view thereof.

Phantom lining, where utilized, is for illustrative purposes only and forms no part of the claimed design.
